CLAIM

The ornamental design for a container for electronic device, as shown and described.

DESCRIPTION

FIG. 1 is an upper perspective view of a first embodiment of a container for electronic device having cover portions shown in an opened position;

FIG. 2 is a lower perspective view of the container for electronic device of FIG. 1;

FIG. 3 is a top plan view of the container for electronic device of FIG. 1;

FIG. 4 is a right side elevation view of the container for electronic device of FIG. 1, the left side elevation view being identical thereto;

FIG. 5 is a bottom plan view of the container for electronic device of FIG. 1;

FIG. 6 is a front elevation view of the container for electronic device of FIG. 1, the rear elevation view being identical thereto;

FIG. 7 is a perspective view of the container for electronic device of FIG. 1, but with the cover portions shown in a closed position and the container for electronic device shown in association with a base unit of a mobile phone;

FIG. 8 is an upper perspective view of a second embodiment of a container for electronic device having cover portions shown in an opened position;

FIG. 9 is a lower perspective view of the container for electronic device of FIG. 8;

FIG. 10 is a top plan view of the container for electronic device of FIG. 8;

FIG. 11 is a right side elevation view of the container for electronic device of FIG. 8, the left side elevation view being identical thereto;

FIG. 12 is a bottom plan view of the container for electronic device of FIG. 8;

FIG. 13 is a front elevation view of the container for electronic device of FIG. 8, the rear elevation view being identical thereto; and,

FIG. 14 is a perspective view of the container for electronic device of FIG. 8, but with the cover portions shown in a closed position and the container shown in association with a base unit of a mobile phone.

The broken lines in the figures illustrate unclaimed portions of the container.
